UNITED STATES PATENT OFFICE.

RICHARD CAHILL, OF BROOKLYN, NEW YORK.

BRUSH.

SPECIFICATION forming part of Letters Patent No. 391,687, dated October 23, 1888.

Application filed January 6, 1886. Serial No. 187,788. (Model.)

To all whom it may concern:

Be it known that I, RICHARD CAHILL, of Brooklyn, Kings county, New York, have invented certain new and useful Improvements 5 in Whisk-Brushes, of which the following is a specification.

The object of my invention is to provide an improved brush for clothes or other wearing-apparel, which shall be made of bristles in the 10 form of a whisk. To this end I construct my improved whisk with a central perforated block, in which the bristles are set so as to diverge in the form of an efficient whisk, and in the top of this block is inserted a peg on which 15 the ornamental handle is secured. By this means I can use bristles of half-length, or long bristles cut in half, so that I can thus use the root end of the bristles for making stiff brushes for cloth, while the "fag" or tip end of the 20 bristles will be used for softer brushes for hats or plush, thereby making a bristle whisk-brush at little expense and of superior quality. The block in which the bristles are set is preferably bound with plush or other ornamental 25 covering, which is secured in peripheral grooves on the edge of the block, and the peg, when inserted in the top of the block, serves to strain and wedge said covering in place and produce a good finish to the construction.

My invention therefore consists in the features above outlined, as hereinafter fully set forth and claimed.

In the drawings annexed, Figure 1 gives a perspective view of my improved brush. Fig. 35 2 is a vertical section of the brush, and Fig. 3 a cross-section on x x of Fig. 2. Fig. 4 is a plan view of the naked block.

Referring to the drawings, more especially Fig. 2, it may be seen that my improved whisk 40 is made up of four distinct parts, instead of the three parts heretofore used in whisks. The said three parts consisted of the fibers or brushing material, the central peg or pin on which the fibers were directly bunched and bound, and the ornamental handle affixed to the projecting end of the peg.

In my improved brush, as seen in Figs. 1 and 2, the four distinct elements are the brushing material or bristles a , the head or block b , 45 into which they are set, the pin or peg c , socketed in said head, and the ornamental handle

d , affixed to the peg. The block b is preferably made of wood in the form of a semicircle, its lower edge being bored with divergent holes, into which the bristles a are set or cemented 55 in bunches in a manner similar to that usual in making bristle brushes, only the holes are rather more divergent and the bunches of bristles are set in with a slight twisting motion, so as to cause the bristles to diverge positively, 60 and thus give the mass of bristles a distinct whisk shape, as shown. The curved periphery of the block b is furrowed with a central groove, e , as seen best in Figs. 3 and 4, which runs into the central hole, f , in which the peg 65 c is socketed.

In order to give an ornamental finish to the brush, the block is bound with plush or other suitable covering, g g , which is preferably cut in two semicircular pieces, which are glued at 70 the lower edge to the straight edge of the block close to the bristles, and are then strained over the curved edge of the block, the curved edges of the plush pieces being brought together and forced into the groove e , which has been previously filled or brushed with glue, thus 75 securely cementing the plush on the curved edges of the block without making a protuberance or seam thereon, as will be understood from Figs. 2 and 3. The lower edge 80 of the covered block is then bound with gimp, h , as seen best in Figs. 1 and 5, giving a fine border finish at the base of the bristles, and the joint of the plush at the groove e is concealed by a strip of gimp, i , run up each curved 85 side of the block and glued thereon, the fag end of the gimp being tucked into the central hole, f , together with the edges of the plush pieces g g near the hole, after which the hole or the peg c is well daubed with glue and the 90 peg is driven into the hole, thus drawing in at the same time the fag ends of the gimp and the plush, and thus straining and fastening the same firmly in place simultaneously with the peg itself. An ornamental hollow handle, 95 d , is then placed over the projecting end of the peg and is glued and tacked thereto, as will be understood from Fig. 2, thus rendering the brush complete, as seen in Figs. 1, 2, and 5.

It will now be seen that by making the 100 whisk with a block, b , intermediate between the central peg and the brushing fibers, instead

of bunching and binding the fibers directly on the peg, as heretofore, I can use fibers of nearly half the length usually employed in whisks; hence short bristles or cut bristles may 5 be used in making the whisk, which is a great advantage. In fact, by this method I can use long bristles cut in half, which are what I employ in making the improved whisks.

For clothes-brushes I use the lower half of 10 the bristles, the root ends being inserted in the block, while the cut ends form the free or brushing ends of the bristles. For softer brushes for hats or fine goods I use the other half of the 15 bristles, the cut ends being inserted in the block while the fag or tip ends form the free or brushing ends, having a fine soft brushing effect. In this way the whisk can be made at half the cost that would be otherwise possible, and a brush is produced which is superior to 20 ordinary whisks heretofore made for brushing clothes, and is even better than most regular bristle clothes-brushes.

The advantage of the bristle whisk over 25 whisks of broom-corn, tampico, or horse-hair is obvious, as before stated, both in durability and in non-injurious effect on the cloth, and as both stiff and soft brushes can be produced by using both halves of the bristles, as I have 30 described; hence the wants in both extremes can be filled much better than are filled at present by broom-corn and horse-hair whisks. It will be further readily seen that the wide diverged form of the bristles in my improved 35 form of brush enables the whisk to cover a good deal of surface at once, yet with a light, effective, elastic touch, which, while not injurious to the nap, is very searching on dust and

fibers on the nap, which it removes rapidly, and yet cleans and frees itself thoroughly of all the material brushed off, as the long elastic 40 divergent nature of the bristles prevents the dust or other matter lodging among the bristles; but it is, on the contrary, rapidly shot out from the bristles and not deposited back again on the clothes, thus making the brush very 45 quick and clean in its brushing action and self-cleaning in itself, which are important advantages over common whisks, as well as over common bristle brushes.

Instead of making the peg *c* and ornamental 50 handle *d* in separate parts, as shown in Fig. 2, they may be made in one solid piece or in two pieces firmly fastened together and before being socketed in the block.

What I claim as my invention is—

1. In a brush substantially as set forth, the central bristle-holding block, *b*, formed with peripheral groove *e*, with ornamental covering *g*, secured in said groove, substantially as set forth.

2. In a brush substantially such as set forth, the combination, with the bristle-holding block *b*, having the central hole, *f*, and peripheral groove *e*, of the ornamental covering *g*, having its edges secured within said groove, binding 65 *i*, over the groove and over the edges of the covering *g*, and handle-pin *c*, driven into said hole with the fag ends of said binding and coverings, substantially as herein set forth.

RICHARD CAHILL.
